UNITED STATES PATENT OFFICE

2,417,173

GAME APPARATUS

James M. Prentice, South Hadley, Mass.

Application August 28, 1944, Serial No. 551,488

1 Claim. (Cl. 273—108)

1

This invention relates to game apparatus and the principal objects of the invention are directed to game apparatus comprising cooperating elements arranged and constructed so that the apparatus may be adapted to simulate various games such as baseball, football, and the like.

The novel features of the invention include a board on which may be disposed the representation of a playing field and playing pieces representing players which a spinner may displace with sockets in the board to receive the playing pieces.

In describing the novel game device reference will be made to the game of baseball but the invention is not to be limited thereto. With the game of baseball various rules of play may be adopted to make use of the cooperating elements of the apparatus.

In the drawings:

Fig. 1 is a plan view of a game board forming a part of the apparatus of the invention;

Fig. 2 is a longitudinal sectional view through the board shown in Fig. 1;

Fig. 3 is an elevational view of a plurality of playing pieces representing players;

Fig. 4 is a similar view showing playing pieces representing other players; and

Figs. 5 and 6 are plan and elevational views of a spinner of the invention.

Referring now to the drawings more in detail, the invention will be fully described.

A game board 2 is shown which has a substantially level floor 4 with a frame 6 extending upwardly at the sides thereof.

The elements of a baseball diamond with positions for the players are represented by 8 and 10. When the apparatus is used for another game than baseball other representations will be used.

The board has an upwardly inclined portion 5 but may not be desired in all cases.

A plurality of playing pieces 12 are shown in Fig. 3. These are preferably cylindrical in form with tapering and curving ends terminating in flat ends, as shown.

The board is provided with a plurality of sockets or holes 14 which are adapted to receive the pieces 12. The said pieces may pass into or through the sockets or may rest angularly therein. The flat ends of the pieces are for supporting them but being rounded they not only may readily enter the sockets 14 but said rounded ends cause the pieces to traverse the board when hit by the spinner to be described.

Other pieces 16 are shown in Fig. 4. These pieces are preferably cylindrical and their lower

ends are receivable in sockets or holes 18 provided in the board 4.

While in the operation of the apparatus the pieces 16 have their lower ends inserted in the sockets 18 they are so arranged that they may be displaced from their sockets by a spinner.

A spinner 20 is provided which is disc-like and has a plurality of flat sides 22 to provide corners 24.

10 A manually engageable stem 26 extends upwardly from the disc and a cylindrical part 28 extends downwardly therefrom which preferably has a flat end, as shown.

The stem may be engaged between the fingers 15 and twirled so that the spinner will spin on the flat end of the part 28. By spinning on the flat end the spinner will while in rotation move around the board so that the corners of the disc may engage and displace one or more of the playing pieces from its position.

Various rules may be adopted to suit the particular game and the playing pieces may be placed according to the rules on the representations on the board.

25 In the operation of the apparatus the spinner is set in motion, on the inclined portion of the board when used, and in its rotation traverses the board so that it may engage and displace the playing pieces 12 and 16 from their position.

When the game is adapted for baseball and the rules are such a playing piece 12 when displaced from its location may indicate a strike. When a playing piece 12 is displaced and enters a socket 14 it may indicate another play, or should a piece 16 be displaced from a socket or the spinner enter a socket the same may indicate other plays.

As stated, the pieces 12 are receivable in the sockets 14 while the pieces 16 are insertable in the sockets 18. The spinner because of its special 40 form is adapted to traverse the board so that it may displace the pieces 16 from their sockets or to displace a piece 12 so that it enters a socket 14.

All together the elements are such as to cooperate and produce according to the rules adopted a very interesting and exciting game.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the append-

ed claim is therefore intended to be embraced therein.

What it is desired to claim and secure by Letters Patent of the United States is:

A game apparatus comprising in combination, a board having a flat surface provided with the representation of a playing field and a starting surface at one end thereof extending upwardly and away therefrom at a relatively slight incline, and said playing field including indications for positioning playing pieces, said flat surface provided in operative association with the playing field with holes for receiving and positioning certain playing pieces and with sockets for other playing pieces, a plurality of certain playing pieces and a plurality of other playing pieces, said sockets adapted to loosely receive said other playing pieces and said other playing pieces being of relatively larger dimensions than said certain playing pieces and holes and adapted to be placed on said indications, a frame at adjacent and opposite sides of said board extending upwardly above the plane of the surface thereof, and an actuator in the form of a spinner having a lower end and radially extending projections adapted to be set 25

in rotation on said starting surface so as to traverse said surfaces and engage and dislodge said certain playing pieces from their holes and the other playing pieces from said indications.
